PORTABLE SERVING STAND

John Hilldale, Venice, Calif., assignor to Wyrefab Inc.,
Venice, Calif., a corporation of California

Application February 21, 1955, Serial No. 34,619

Term of patent 14 years

(Cl. D33—14)

FIG. 1.

FIG. 2.

FIG. 3.

FIG. 4.

Fig. 1 is a plan view of a portable serving stand;

Fig. 2 is a front elevational view of a portable serving stand;

Fig. 3 is an end elevational view of a portable serving stand; and

Fig. 4 is a horizontal sectional view taken on the broken line 4—4 of Fig. 2.

I claim:

The ornamental design for a portable serving stand, as shown.
